W. P. JONES

WIRE CLOTH STRETCHING MACHINE

Filed April 22, 1926

FIG. 1.

FIG. 2.

FIG. 3.

William Peter Jones:
INVENTOR

Patented Nov. 15, 1927.

1,649,350

UNITED STATES PATENT OFFICE.

WILLIAM PETER JONES, OF DOVER, NEW JERSEY.

WIRE-CLOTH-STRETCHING MACHINE.

Application filed April 22, 1926. Serial No. 103,997.

The invention relates to machinery and mechanical devices, having for their purpose the stretching of wire-cloth or other tough fabric, coming in rolls, over wooden, metallic or other framework preparatory to being attached to same by tacks, nails, screws, bolts, rivets, glue or otherwise, and the objects of the invention are, first, to afford a simple and convenient method of unrolling and stretching wire-cloth or other tough fabric, coming in rolls, over wooden, metallic or other framework, insuring uniformity of surface and eliminating wire-cloth or fabric wastage through tearing; second, to reduce the shop space ordinarily required for wire-cloth or fabric stretching and fastening operations; third, to provide facilities for stopping the wire-cloth or fabric stretching and fastening operations without necessitating a duplication of work already performed when resuming the task; and, fourth, to save time and labor by reducing the number of hands required to perform wire-cloth stretching or fastening operations.

One form of the invention is illustrated in the accompanying drawing, in which Fig. 1 is a plan view of the machine as it appears in actual operation when "loaded" with a roll of wire-cloth; Fig. 2, a vertical section of the machine from the side; and Fig. 3, a detailed, full-faced view of the machine from its front end.

The table or plate 1, represents the work-table or bench upon which the two adjustable, parallel basic uprights 2 2, are fastened, to any desired width, by means of angle brackets, 21 21, and lag screws.

The two eccentric cams, 6^A 6^B, are fastened to the top of table 1 but beneath retainer 5 by means of rivets 7 7.

Between stationary retainer 5 and movable top clamp 3 is a thin opening both edges of which are faced with strips of metallic packing, wire clamping, 23 and 24, or other suitable material to prevent tearing of the wire-cloth or fabric 16 as it comes through said opening off the roll 12, which is horizontally supported by cylindrical roller 13 and clamps 14 14 attached to angle brackets 45 15 15 which, in turn, are fastened to the rear edges of basic uprights 2 2.

Movable top clamp 3, which is operated by the two eccentric cams 8^A 8^B fastened inside the slot provided in the two basic uprights 2 2 by means of bolts 9 9, washers 10 10 and nuts 11 11, is rendered adjustable by

two spiral compression springs 20 20 inserted between the lower extremities of movable top clamp 3 and the upper extremities of stationary retainer 5. Movable top 60 clamp 3 is rendered proof against slipping or sliding sideways by the two dowels 19 19 inserted through top clamp 3 3 at right angles thereto and parallel with and resting against the face of the inside of the basic uprights 2 2.

Adjustable brace 4, fastened to the front edges of basic uprights 2 2, renders the framework more secure.

Brackets and bearings 26 26 attached to 70 side of work table or bench 1 in conformity with width of adjustable, basic uprights 2 2, by means of parallel slots in work table, support roller-rod 27 beneath which wire-cloth or fabric 16 passes on its way to the further 75 extremity of screen or other framework 17 the upper edge of which said framework is placed snugly against the heads of eccentric cams 6^A 6^B which, when operated by their handles, push screen or other framework 17 80 forward so that wire-cloth or fabric 16, tacked or otherwise fastened to lower end of framework 17 by tacks 25, is stretched and flattened to any desired degree between wire-cloth or the fabric roll 12 and the lower end 85 of the framework 17.

When the desired degree of tautness has been attained, the same may be maintained by operating the eccentric cams 8^A and 8^B 90 which exert pressure upon the movable top clamp 3, thus securing the wire-cloth or other fabric between the stationary retainer 5 and the movable top clamp 3.

The work of completing the tacking, nailing, screwing, bolting, riveting, gluing or otherwise fastening of the wire-cloth or other fabric to the framework may then be immediately finished or it may be discontinued for the time being without the necessity of going over the stretching and fastening operations again, as would otherwise be the case.

In stretching and fastening wire-cloth or other fabric over certain frames where the weight of the frame would be insufficient to permit of much stretching either because of the material of which made or because of the small size of the frame, it is advisable to fasten a protruding clamp 18 to the lower end 105 of the framework 17 which said clamp 18 works in sliding, adjustable members or supports 22, 22, attached to the table or bench 110

2
1 whereby stability of the framework is ensured for stretching and fastening purposes.

While I have illustrated and described my invention with some degree of particularity, I realize that in practice various alterations therein may be made. I therefore reserve the right and privilege of changing the form of the details of construction or otherwise altering 10 the arrangement of the correlated parts without departing from the spirit of the invention or the scope of the appended claims.

Having thus described my invention what I claim as new and desire to secure by United 15 States Letters Patent is:—

1. A stretching device for stretching material across a frame, comprising a base, means for supporting the roll of material at one end of the base, a plurality of individually operable cam members for moving the frame to which the material is to be applied, guides on the base for said frame, and a clamp between the frame and the roll for securely holding the material to be stretched.

2. A stretching device for stretching ma-

terial across a frame, comprising a base, uprights for supporting a roll of material adjacent one end of the base, a plurality of individually operable cam members pivoted to the base for moving the frame to which the material is to be applied, guides on the base for said frame adapted to prevent the raising of one end of the frame from the base and a clamp between the frame and the material roll securely holding the material to be stretched.

3. A stretching device for stretching material across a frame, comprising a base, means for supporting a roll of material at one end of the base, a plurality of members pivoted to the base for moving the frame to which the material is to be applied on the base for said frame, resiliently opposed clamping members disposed between the frame and the roll and a plurality of cam members for operating said clamp members whereby the material to be stretched will be securely held.

WILLIAM PETER JONES.
